Oscar Geier

UNITED STATES PATENT OFFICE.

PETRO TATARYN, OF CHESTER, PENNSYLVANIA.

FARM-FENCE.

1,228,717.

Specification of Letters Patent.

Patented June 5, 1917.

Application filed March 2, 1917. Serial No. 151,933.

To all whom it may concern:

Be it known that I, PETRO TATARYN, a subject of the Emperor of Austria, resident of Chester, county of Chester, and State of

5 Pennsylvania, have invented certain new and useful Improvements in Farm-Fences, of which the following is a specification.

This invention relates to improvements in farm fences, and particularly to types 10 known as portable and adjustable.

The principal object of the invention is to provide a fence which by means of its sectional construction may be moved to enclose such areas as are desired, each of the 15 sections being independently adjustable as to length and also in height.

This and other like objects are attained by the novel construction and combination 20 of parts hereafter described and shown in the accompanying drawings, forming a material part of this specification, and in which:—

Figure 1 is a perspective view showing a complete section of the same.

25 Fig. 2 is a fragmental side elevational view showing the bottom portion of one of the posts or supports.

Fig. 3 is an enlarged sectional view taken through one of the posts, and

30 Fig. 4 is a front side elevational view of the same.

The fence is composed of a plurality of post elements 10, the lower end of which is set in the ground a short distance so as to steady the same, while level with the surface of the ground are transverse bars 11 extending equally outward upon each of the four sides of the post and having at their ends braces 12 angularly disposed and attached to the posts midway in their height.

40 Passing transversely through the post 10 are a plurality of pairs of holes 14 in which may be secured bolts 15 having an angularly turned end 16 between which and the collar

45 17 is a thin sleeve or ring 18 so that as the nut 19 is turned, drawing the bolt into rigid engagement with the post, a definite space is provided between the upturned end 16 and the face of the post 10 to receive the fence 50 rails 20, slots 21 being provided near their adjacent ends suited to pass freely over the sleeves 18.

Thus each of the rails 20 may be removed from engagement with the post or arranged

upon other bolts at different heights thereby 55 changing the space between adjacent rails so that a fence of varying height may be made.

In order to render the sections extensible, center rail elements 25 are provided which 60 may be independently bolted through openings 26 to a vertical bar 27 and held in position by the bolts 28 as clearly indicated in Fig. 1.

At the adjacent ends of the rails 20 and 65 25 are secured cleats 30 provided with a plurality of apertures 31 receivable of the pins 32 so that the pins permit of moving the elements 20 longitudinally with respect to the rails 25, thereby extending or contract- 70 ing the spaces between the posts 10 as may be desired.

It will be further evident from the construction shown that the fence is readily dismembered and that the central section 75 25 may be so turned with relation to the longitudinally disposed rails shown bolted to it that the whole may be packed very compactly within a small space when not actually required in use, thus providing a sec- 80 tional portable fence having adjustable elements which may be readily transported and erected at desired points.

Having thus described my invention, what I claim as new, and desire to secure by Letters Patent, is:—

In a fence of the class described, the combination with posts having transverse elements rigidly attached at the lower end and containing a plurality of paired openings 90 passing transversely therethrough, bolts engageable in said openings, said bolts having a hooked outer end, a sleeve and washer on said bolts whereby they are permitted to be drawn tightly against the base of said post, 95 longitudinally disposed main rails having slots extending from their lower side toward their center adjacent to one end thereof, connecting rails engaging with said main rails disposable between pairs, cleats com- 100 bined with said main and connecting rails whereby the same may be held in alinement, and bars disposed centrally between said posts to which said connecting rails are attached.

105 In testimony whereof I have affixed my signature this 15 day of February, 1917.

PETRO TATARYN.
